UNITED STATES PATENT OFFICE.

ERNEST A. ESSMUELLER AND LEWIS D. HUGGINS, OF ST. LOUIS, MISSOURI.

ONE-PIECE BUTTON AND BUCKLE.

1,386,339.

Specification of Letters Patent.

Patented Aug. 2, 1921.

Application filed March 29, 1920. Serial No. 369,552.

To all whom it may concern:

Be it known that we, ERNEST A. ESSMUELLER and LEWIS D. HUGGINS, both citizens of the United States, residing in the 5 city of St. Louis and State of Missouri, have invented new and useful Improvements in One-Piece Buttons and Buckles, of which the following is a specification, reference being had to the accompanying drawings.

10 The present invention is in the nature of a one piece button and buckle, for use as a fastening on garments and straps and in the making of garments.

15 The primary object of the invention is to provide an efficient fastening in the way of a one piece button and buckle which may be strongly and cheaply constructed in one piece, or stamped out from one piece of sheet metal.

20 A secondary object is to provide a fastening of this nature, the buckle portion of which may be permanently attached to one portion of the garment or to one end of the strap, while the button portion may be detachably locked in a button hole formed in another portion of the garment or in the other end of the strap.

With these ends in view, attention is called to the accompanying drawings, wherein:

30 Figure 1 is a plan view of such a one piece button and buckle.

Fig. 2 is an edge view.

Fig. 3 is a perspective view showing the fastening as mounted upon and adapted to 35 connect the two ends of a strap.

Fig. 4 is a detail showing how the teeth of the buckle portion engage the strap.

In carrying out the invention in its embodiment as illustrated in the drawings, we 40 take a single piece of sheet metal and stamp same out so as to form a rectangular buckle portion consisting of a frame 1 having a central cross bar 2, and an integral button portion 3 which is connected to the buckle portion by means of a narrow neck portion 4. The cross bar 2 is provided with teeth 5 punched downward from the cross bar 2 and adapted to pierce through the strap 6, or other material, and then to be pressed

back firmly against the strap, for the purpose of locking that end of the strap firmly to the buckle. The button 3 is preferably convexo-concave, being convex at its upper or outer side and concave at its lower or inner side, thus forming a smooth and button-like appearance, and at the same time adding strength to the structure. The neck 4 is bent slightly out at its point of juncture with the button 3, as means for more readily and smoothly engaging the button hole 7 formed in the opposite end of the strap 6, while the forward end of the button itself is bent slightly downwardly or inwardly. This construction has been found to most efficiently serve the purpose of such a fastener.

While we have herein described a certain specific method of constructing and assembling the elements of our invention, it is understood same may be varied in minor details, not departing from the spirit of our invention as defined in the appended claims.

What we claim to be new and patentable is:

1. The combination of a strap having a 75 button hole at one end, a one piece buckle and button having in its buckle portion a bar intermediate its ends, the opposite end of the strap being clenched to said bar, the button being spaced from the buckle portion 80 by a reduced neck bent slightly outwardly at its outer end to offset a portion of the button from the longitudinal axis of the buckle portion, the outer part of the button lying substantially in the plane of the buckle portion.

2. The combination of a strap having a button hole in one end, a buckle and button connected together by a reduced neck portion, the buckle portion having a bar intermediate its ends, the bar having teeth struck up therefrom, the opposite end of said strap being secured to said bar by said teeth.

ERNEST A. ESSMUELLER.
LEWIS D. HUGGINS.
